UNITED STATES PATENT OFFICE.

JOHN D. MILLER, OF DETROIT, MICHIGAN, ASSIGNOR TO DETROIT STOVE WORKS,
OF SAME PLACE.

DESIGN FOR A HEATING-STOVE.

Specification forming part of Design No. 5,301, dated October 3, 1871.

To all whom it may concern:

Be it known that I, JOHN D. MILLER, of Detroit, in the county of Wayne and State of Michigan, have invented and produced a new Design for a Heating-Stove, reference being had to the accompanying drawing and to the letters of reference marked thereon, and being a part of this specification, in which my design is shown in perspective.

I claim as my invention—

1. The design for the legs or feet, substantially as shown.

2. The design for the base, substantially as shown.
3. The design for the door, substantially as shown.
4. The design for a stove, substantially as shown.

JOHN D. MILLER.
